UNITED STATES PATENT OFFICE.

GEORGE H. PARSLAW, OF CHILLIWACK, BRITISH COLUMBIA, CANADA.

DESIGN FOR A POISON-BOTTLE.

43,179.

Specification for Design.

Patented Oct. 22, 1912.

Application filed March 27, 1912. Serial No. 686,711. Term of patent 7 years.

To all whom it may concern:

Be it known that I, GEORGE H. PARSLAW, a subject of the King of Great Britain, and residing at Chilliwack, in the Province of British Columbia, Canada, have invented a new, original, and ornamental Design for Poison-Bottles, of which the following is a specification, reference being had to the accompanying drawing, forming part thereof.

The figure is a plan view of a poison bottle, showing my new design.

I claim:—

The ornamental design for a poison bottle as shown.

GEORGE H. PARSLAW.
